(57) CLAIM

The ornamental design for a hand portion of an oven mitt, as shown and described.

DESCRIPTION

FIG. 1 is a front elevational view of a first embodiment of a hand portion of an oven mitt showing my new design, the rear elevational view being a mirror image thereof;

FIG. 2 is a right side elevational view thereof;

FIG. 3 is a left side elevational view thereof;

FIG. 4 is a top plan view thereof; and,

FIG. 5 is a bottom plan view thereof.

The speckling indicates a terrycloth-like rough surface.

The dashed line indicates stitching.

The phantom line indicates only an environment of use and is not a part of the claimed design.
